UNITED STATES PATENT OFFICE.

EDWIN H. BAARE, OF ST. LOUIS, MISSOURI.

LAMP-SHADE HOLDER.

Application filed July 16, 1925. Serial No. 43,920.

This invention relates to new and useful improvements in lamp shade holders, the objects being to provide a lamp shade holder or frame adapted to removably receive any one of a series of interchangeable adapters or center pieces whereby such a shade holder can be used in combination with various styles of lamp fixtures.

Further objects of the invention are to provide a series of adapters or attaching members having their central portions variously formed in order to permit said adapters to be attached to various lamp fixtures. The annular flanges of said adapters are similarly formed for enabling any one of said adapters to be attached to a receiver portion of a lamp shade holder.

Other objects of the invention are to provide simple means for securely interlocking the shade frame with a removable member, the latter being adapted to be attached to a lamp fixture.

With these and other objects in view, my invention consists in certain novel features of construction and arrangement of parts, hereinafter more fully described and claimed, and illustrated in the accompanying drawings, in which—

Figure 1 is a view showing a shade attached to a table lamp.

Figure 2 is a top plan view of the upper end of a lamp shade frame showing one form of an adapter in dotted lines in readiness to be attached to said shade frame.

Figure 3 is a vertical cross section taken through the upper end of the shade frame shown in Figure 2.

Figure 4 is a top plan view of an adapter used in attaching a lamp shade to a table lamp or similar lamp fixture.

Figure 5 is a side elevational view of the adapter shown in Figure 4.

Figure 6 is an enlarged cross sectional view showing the adapter attached to a lamp fixture and in engagement with the lamp shade frame.

Figure 7 is a top plan view of an adapter adapted to be attached to a lamp socket.

Figure 8 is a vertical section through the same showing a lamp socket in dotted lines.

Figure 9 is a vertical cross section through a modified form of adapter designed to be attached to a lamp socket and provided with a tubular extension for receiving a glass shade.

Figure 10 is a perspective detail view of the adapter shown in Figures 4 to 6.

Figure 11 is a fragmental plan view of the lamp shade frame with one of the adapters secured in position therein.

Figure 12 is a modified form of adapter adapted to be attached to the bulb of a lamp.

Heretofore, lamp shade frames were made to fit only one form of a lamp fixture and consequently it was necessary to carry a large stock of lamp shades for use with the various styles of lamp fixtures. Where a particular shade was desired and such a shade was not equipped for use with the particular lamp, it was necessary to cut the wires carrying the supporting frames of said shade and replace it with another supporting plate or center piece adapted for use with the particular lamp. Such a procedure was both costly and unsatisfactory and the dealers would lose sales through being unable to supply a particular shade for use with a particular lamp.

It is the purpose of the present invention to provide a lamp shade which may be attached by the use of a suitable adapter or holder to fit any of the various kinds of lamps and also to provide holders or adapters to raise or lower the shade so desired.

Referring by numerals to the accompanying drawings, and particularly to Figures 1 to 6 inclusive, 10 indicates a lamp having a standard 10° and a shade 11. Shade 11 is arranged on a shade frame 12, the upper end of which comprises an outer ring 14 and an inner ring 15 which rings are connected together by cross pieces 16. Secured to ring 15 and projecting inwardly therefrom is a collar 17 the inner edge of which is provided with inwardly opening notches 18 and eccentrically disposed portions or cams 19, notches 18 being disposed between adjacent ends of the respective cam portions 19. The outer edge of cam or ring 17 is slotted or apertured as indicated at 20 in order to permit the attachment of suitable cover material to ring 15. It will be understood that shades are formed in various shapes and sizes for various purposes, but all of such shade frames are equipped with collars 17 which are of standard sizes and dimensions to fit various forms of adapters which are also formed of standard dimensions.

The form of adapter shown in Figures 4 to 6 inclusive, which form is adapted for use with table lamps, floor lamps, and similar styles of lamps, comprises a plate 21 provided with a central aperture 22 which is designed to receive the threaded portion 10^a of a lamp standard 10^a and is adapted to be secured in position on standard 10^a by a nut 10^c threaded on portion 10^b. The annular portion of plate 21 is cut at suitable intervals as indicated at 24 to provide projecting flat portions 25 and tongues or fingers 26, which latter are bent upwardly and outwardly as indicated at 27 in order to space or offset the extensions 28 thereof a suitable distance from portions 25. The distance between the planes of tongues 28 and portions 25 is substantially equal to the thickness of plate or collar 17 which, when the adapter is in position, is engaged between said fingers and portions 25 as shown in Figure 6. The peripheral spacing of tongues 28 coincides with the arrangement of notches 18 of collar 17 and the width of said tongues is slightly less than the width of said notches so that said tongues can be passed therethrough in attaching the adapter to the lamp shade frame.

Plates 21 are of greater diameter than the diameter between the portions 19 and when said plate is attached to the shade frame, the edges of portions 25 and tongues 28 overlap the edges of portions 19, thereby securely holding the adapter in position in the frame. The eccentricity of portions 19 facilitates the insertion of the adapter in ring 17 and provides frictional engagement between the edges of said portions 19 and the laterally disposed portions 27 of tongues 28, thereby interlocking said parts together.

To place the adapter in position in the frame, said adapter is placed in the position shown in dotted lines in Figure 2, with the portions 19 occupying medial position between the tongues 28 and portions 25. The adapter is then partially rotated in the direction indicated by the arrow so as to bring tongues 28 in engagement with portions 19 and frictionally engage the portions 27 of tongues 28 with the eccentrically disposed edges of portions 19 as shown in Figure 11.

In Figures 7 and 8 a modified form of adapter is shown, particularly designed for attachment to a lamp socket. The adapter comprises member 29 provided with a comparatively large central opening formed by a tubular extension 30 which is attached to said adapter and is threaded for receiving the threads of a lamp socket 31. The attaching portions 25 and 26 are formed in the same manner as the adapter previously described to receive the portions 19 of the lamp shade frame.

In the form shown in Figure 9, an adapter 32 has a tubular extension 34 which termi-

nates in an outwardly presented annular flange 35 adapted to be engaged by screws 36 of a shade holder 37, now commonly used, where it is not desired to remove such holder 37. A threaded tubular extension 32^a may be provided so that said adapter can be attached directly to the lamp socket.

In the form shown in Figure 12, an adapter 38 is provided with flexible fingers 39 which are designed to engage bulb 40 of a lamp, thereby supporting said adapter in position thereon. This adapter is particularly arranged for use for supporting or attaching shades to electric candle sticks.

In all of the various forms of adapters, with the exception of those shown in Figures 9 and 12, attaching portions 25 and 26 are formed alike in form and size so that any one of said adapters can be used in combination with any style of shade.

I claim:

1. A lamp shade holder comprising a frame member, a centrally disposed ring secured at its outer edge to said frame and having its inner edge formed with eccentric portions, and radially disposed notches, and an adapter having a horizontally disposed annular edge of greater diameter than the opening in said ring for bearing against one side thereof and formed with lugs offset in a horizontal plane with respect to said annular portion and adapted to pass through said radial notches for engaging the opposite side of said ring, said adapter being provided with a central opening for receiving a lamp fixture.

2. A lamp shade holder comprising a wire frame, a circular member secured to said frame and provided with a central opening having segmental eccentrically disposed edge portions and radially presented notches, and an adapter adapted to be attached to a lamp fixture and provided with a horizontally disposed flanged portion of a diameter greater than the diameter of said central opening whereby said flanged portion engages one side of said circular member, said flanged portion being formed with lugs offset in a horizontal plane with respect thereto for frictionally engaging said circular member on the opposite side, said eccentrically disposed edge portions being adapted to frictionally engage peripheral faces formed on said adapter, thereby holding said adapter and said circular member against disengagement with respect to each other.

3. A lamp shade holder comprising a lamp shade frame, a receiver member secured thereto and provided with a central opening, the edge of said opening being formed with a plurality of eccentric edge portions, and a center piece adapted to be attached to a lamp fixture and provided in its annular edge with portions for frictionally engaging

the opposite faces of said eccentric portions of said receiving member, said eccentric portions being adapted to frictionally engage arcuate peripheral faces of said center piece 5 for frictionally locking the latter against displacement.

4. A lamp shade holder comprising in combination a lamp shade frame, a receiver member secured thereto and provided with 10 a central opening and having a series of radial notches opening thereinto, and a center piece adapted to be attached to a lamp fixture and having radial portions offset in a horizontal plane relative to the flange portion 15 of said center piece and adapted to pass through said notches for frictionally engaging one side of said receiver member, the flanged portion being adapted to engage the other side of said center piece.
- 20 5. A lamp shade holder comprising in combination a shade frame, a receiver member secured around its annular edge to said frame and having a central opening provided with eccentrically presented cam 25 portions and radial notches communicating with said central opening, and an adapter adapted to be secured to a lamp fixture and having an annular flange formed with a series of radial lugs offset in a horizontal plane 30 relative to said flange and adapted to pass

through said notches for engaging and interlocking said cam portions between said lugs and said annular flange of said adapter, and said eccentric portions being adapted to frictionally engage portions of said lugs 35 to form an interlock between said holder and said adapter.

6. A lamp shade holder comprising in combination a shade frame, a receiver member secured to said frame and having a central opening formed with eccentrically presented edge portions and radially disposed notches communicating with said central opening, and an adapter adapted to be secured to a lamp fixture and having a marginal flange formed with a series of spaced fingers offset in a horizontal plane with respect to said flange and adapted to pass through said notches for engaging one side 40 of said eccentrically presented portions between the said marginal flange portions of said adapter and said spaced portions, said eccentrically presented portions being designed to frictionally engage portions of said spaced fingers and hold said adapter against 45 displacement.

In testimony whereof I hereunto affix my signature this 2nd day of July, 1925.

EDWIN H. BAARE.
